REFRIGERATOR CABINET

Homer E. Rosebrook, Greenville, Mich., assignor
to Gibson Refrigerator Company, Greenville,
Mich., a corporation of Michigan

Application July 15, 1948, Serial No. 38,899

1 Claim. (Cl. 62—103)

1

This invention relates to refrigerator cabinets, and more particularly to the arrangement of drip pans and partitions therein.

The present invention is particularly adapted to refrigerators having evaporators which are substantially coextensive, at least laterally, with the horizontal internal dimensions of the storage chamber.

It is the practice in some refrigerators of that type to place a drip pan beneath, and relatively close to the evaporator. Below the drip pan and spaced therefrom is an imperforate shelf which acts as a partition between the space thereabove and therebelow. At the front of the cabinet between the main closure and the evaporator are two coplanar auxiliary closures for the evaporator section and the space between the drip pan and the partition.

By means of such an arrangement it is possible to produce three quite different temperatures within the storage chamber, a sub-freezing temperature in the evaporator section above the drip pan, a low, but above freezing temperature between the drip pan and the horizontal shelf below it, and a still higher temperature below the shelf just mentioned. To produce a relatively wide temperature differential between the sections the drip pan is nearly the same size as the horizontal dimensions of the storage chamber behind the auxiliary closures so as to restrict the circulation of air between the spaces above and below the drip pan. On the other hand, the first shelf below the drip pan should be of such dimensions as to only slightly restrict the flow of air between the spaces above and below it. Both the drip pan and the first shelf below it should preferably have low coefficients of heat transmission.

As can be readily seen, this arrangement does not permit of varying the capacity of the coldest section of the refrigerator by varying its dimensions.

Accordingly, the principal object of the present invention is to provide in a refrigerator cabinet of the character described a movable drip pan and a combination imperforate partition and shelf, so constructed and arranged as to provide great flexibility of temperature conditions in zones adjacent the evaporator.

Another object is to provide a movable drip pan which can be removed from its position adjacent the evaporator and lowered to a new position whereby to substantially increase the frozen food storage space while still retaining its capacity as a drip pan.

Another object of the invention is to provide a novel form of drip pan.

2

These objects, as well as others, will become clearly apparent in the following description of the invention, when read in connection with the accompanying drawings, wherein:

5 Figure 1 is an elevational view of a refrigerator cabinet embodying the invention, the usual door of the cabinet being removed;

Figure 2 is a fragmentary cross-sectional view taken on substantially the line 2—2 of Figure 1;

10 Figure 3 is a fragmentary cross-sectional view on an enlarged scale of the drip pan and adjacent parts, taken on substantially the line 2—2 of Figure 1;

Figure 4 is a fragmentary front elevational view of the drip pan when the latter is mounted in one auxiliary position within the cabinet;

15 Figure 5 is a fragmentary cross-sectional view on an enlarged scale taken on substantially the line 2—2 of Figure 1, showing the drip pan in another auxiliary position;

Figure 6 is a plan view of the drip pan;

Figure 7 is a fragmentary cross-sectional view taken on substantially the line 7—7 of Figure 6; and

20 Figure 8 is a fragmentary cross-sectional view of a modified form of drip pan.

This invention is illustrated as being embodied in a refrigerator of the household type. The refrigerator comprises an insulated cabinet 10 having therein a refrigerated food storage chamber 11. The chamber 11 is provided with an access opening closed by an insulated door 12.

25 An evaporator 13 for cooling the interior of the food storage chamber 11 is mounted in the latter adjacent the top thereof. The evaporator preferably is of generally rectangular box shaped form, of any well known construction, open at the front. Preferably the evaporator 13 extends substantially from front to rear and from side to side of the chamber 11.

30 Below the evaporator are a plurality of shelves 14 and 15. The shelves may be of any suitable type, either of open grid construction, or of imperforate form. The shelf 14, however, is an imperforate plate, preferably of glass, which forms a partition between the spaces thereabove and therebelow.

35 The shelf 14 is spaced slightly from all of the upright sides of the cabinet, permitting a restricted flow of air between the space above the shelf and the space below it. The flow of air is restricted to a sufficient extent, however, so that the temperature of the air immediately above the shelf is maintained near, but not quite 32° F., while the space below the shelf is maintained at a temperature somewhat higher, preferably in

the neighborhood of 42° F. In order that proper circulation will be maintained, the side edges of the shelf are positioned quite close to the cabinet side walls, but a fairly large gap is formed at the rear edge of the shelf. See Figure 5.

Between the door 12 and the shelf 14 and evaporator 13 are two auxiliary closures 16 and 16a. Preferably the closures are formed of glass. They are hinged at their lower edges, on horizontal axes, to the sides of the refrigerator cabinet. The closures 16 and 16a are positioned close to, but not quite touching, the evaporator and the shelf 14. The closures act to restrict the flow of air between the spaces above and below the shelf 14, as well as assist in preventing entrance of heat to the space above the shelf 14 when the door 12 is opened.

A drip pan 17 normally is positioned below and in relatively close proximity to the evaporator 13, as shown in full lines in Figure 2. The drip pan is a shallow pan, preferably formed of plastic, to reduce the transmission of heat therethrough. The drip pan is slightly deeper at the rear edge than at the front, so that moisture dripping therein will flow toward the back. Four legs 17a are formed on the bottom of the drip pan to support the bottom wall in an inclined position when the drip pan is located in an auxiliary position as shown in Figure 5, and which will be described presently.

The front edge of the drip pan is curved upwardly at 18, as shown in Figures 1 and 3, to assist in collecting moisture, and to provide a handle. A narrow groove 18a is formed in the drip pan bottom adjacent the perimeter thereof. This groove collects moisture dripping into the pan and conducts it to a drain opening 18 at one rear corner of the drip pan. By means of the groove and the drain opening the major part of the drip pan is kept clear of moisture so that the drip pan can be used as a storage shelf, and the drip can be collected in a suitable receptacle placed beneath the drain opening 18.

The drip pan is also provided with an air circulating opening adjacent the front edge thereof. The opening is an elongated slot extending nearly the full width of the drip pan. The opening is surrounded by an upturned flange 20 to prevent moisture from running out through the slot.

A baffle 21, inclined upwardly and rearwardly, overhangs the slot at the front of the drip pan, in order to prevent moisture falling from the evaporator 13 from continuing directly through the drip pan into the space therebeneath.

Provision is made for removably supporting the drip pan 17 in the full line position in Figure 1, or in a position below the shelf 14, the latter position being shown in broken lines in Figure 1. The supporting means may take various forms, but in the present instance the supports are channels 22a attached to the inner side walls of the cabinet. See Figure 4. The channels 22a receive side flanges 22 extending laterally from the drip pan. The flanges slide in the channels 22a.

By means of the supporting channels 22a the drip pan may be selectively located in either of the two positions shown in Figure 1. When the drip pan is located in the full line position directly beneath the evaporator, it not only serves as a drip collector, but acts as a partial insulator between the evaporator and the space above the shelf 14 and the drip pan. The circulation of air between the various spaces within the chamber 11 is thereby limited, and the temperature within the space between the drip pan and the shelf

14 is maintained at a temperature above freezing but below the temperature of the space below the shelf 14.

On the other hand, the temperature in the space above the shelf 14 may be lowered to freezing by removing the drip pan from the full line position and placing it in the broken line position in Figure 2. Removal of the drip pan from the full line position increases the frozen food storage space materially, because it puts the entire space above shelf 14 into direct communication with the evaporator 13.

At the same time, the drip pan still retains its function as a drip collector because it underlies the shelf 14 and the closures 16 and 16a. When the entire space above shelf 14 is used for frozen food storage, the evaporator will not be defrosted. Therefore, the only drip which must be collected by the drip pan is that condensing on the closures 16 and 16a and the shelf 14. This moisture runs down the faces of the closures into the drip pan 17, or drips from the underside of the shelf 14.

In order that the drip pan 17 may be utilized as a drip collector in both of its positions, it is important that suitable stops, such as abutments 23 at the rear ends of the lower channels 22a, be provided to prevent the drip pan in its lower position from sliding too far rearwardly, so that the front edges of the drip pan be not located beneath the closure 16.

The drip pan may be used as a removable drawer, if desired, in which food can be stored. Articles so stored must be relatively low in height. In addition, the drip pan may be placed directly upon shelf 14, as shown in Figure 5, permitting the insertion into the refrigerator or removal therefrom of relatively large quantities of food at one time. When so arranged the legs 17a support the bottom of the drip pan in a downwardly and rearwardly inclined position.

The arrangement of parts described, namely, the evaporator 13, shelf 14, closures 16 and 16a, and drip pan 17, provide compartments in the upper part of the food storage chamber through which air circulation is substantially restricted. During normal operation, when the drip pan is in the full line position, air can circulate between the evaporator space and the space therebelow only through the restricted openings between the rear and side edges of the drip pan and the corresponding side walls of the chamber, and through the slot in the drip pan defined by flange 20. Air can circulate between the spaces above and below the shelf 14 only through the restricted openings between the shelf 14 and the chamber side walls. Thus, three different temperatures in the three zones are maintained.

When the drip pan is mounted as shown in broken lines in Figure 2, the freezing temperature space is materially enlarged, while the higher temperature desired in the space below shelf 14 is maintained by the restricted openings around the shelf 14.

The drip pan may be formed of sheet metal, if desired. However, sheet metal is a relatively good conductor of heat. Therefore, it is desirable to insulate the drip pan in some manner to reduce the transmission of heat therethrough.

One manner of insulating the drip pan is illustrated in Figure 8, wherein the drip pan is composed of two separate pans 30 and 31, similar in shape, arranged in spaced apart nested relation. The upper drip pan is identical with drip pan 17 and has a perimetral flange 32. The lower pan is similar in shape but has no perimetral flange. Also, the lower pan 31 has a per-

imetal groove 33 of larger dimensions than the groove in the pan 30.

The two pans 30 and 31 are attached together by means of a plurality of bolts 34, and held in spaced relation by spacers 35 of rubber or similar insulating material. Both pans are provided with drain openings 36 and 37.

The drip pan shown in Figure 8 is used in the same manner as drip pan 17, being supported by flange 32 in the guides 22a previously described, 10 or being laid upon shelf 14.

Consequently, it will be seen that the present invention provides great flexibility in operation of the refrigerator in a simple and inexpensive manner.

The scope of the invention is indicated in the appended claim.

I claim:

In a refrigerator cabinet having an evaporator compartment and a second compartment immediately below said evaporator compartment, said compartments being substantially coextensive horizontally with the interior of said cabinet and having provision for air communication between said compartments, the improvement 20
25

15

which comprises a drip pan baffle substantially coextensive in a horizontal direction with said compartments, means in said cabinet for removably mounting said drip pan baffle at the top of said second compartment, and means in said cabinet for removably mounting said drip pan baffle at the bottom of said second compartment said drip pan baffle being capable of association with said evaporator compartment or said second compartment whereby to change the temperature of the second compartment and to collect drip from said second compartment as well as drip from said evaporator compartment.
